WORK SUPPORTING OR FEEDING DEVICE

Albert N. Hoffmann, Cincinnati, Ohio, assignor to
The American Laundry Machinery Company,
Cincinnati, Ohio, a corporation of Ohio

Application June 11, 1947, Serial No. 753,913

10 Claims. (Cl. 271—61)

1

This invention relates to work supporting or feeding devices, such as are used for supporting a stack of towels in position to be fed manually to a folding machine or other apparatus.

One object of the invention is to provide an improved work support of very simple form, capable of attachment either to new machines or to machines already in use, which will accommodate towels or other articles of any size or shape, which presents to view that edge of the article which is fed first to the machine, which places that edge very close to the feeding belts or apron, which does not require the towels or other articles to be draped symmetrically or in balanced position across a bar, and which is adjustable to present either a smooth surface or a rough surface to the bottom of the stack, thus both facilitating adjustment of the stack to the support and preventing movement of the stack when it is laid in place.

Further objects of the invention in part are obvious and in part will appear more in detail hereinafter.

In the drawings, Fig. 1 is a side elevation, showing the device attached to a folding machine;

Fig. 2 is a plan view;

Fig. 3 is a bottom plan view, in the direction of the arrows 3—3, Fig. 1;

Fig. 4 is a section view enlarged, on the line 4—4, Fig. 3;

Fig. 5 is a similar view, showing another position of the retaining pads; and

Fig. 6 is an enlarged fragmentary perspective view, showing one end of the apron bar and bracket.

In Fig. 1, 10 represents more or less diagrammatically any machine with which the invention may be used, such as a machine for folding towels, pillow slips or the like, to the folding mechanism of which (not shown) the towels are led by belts or a traveling apron indicated at 11. The operator lays or arranges the towels on the apron, one by one, straightening them out as she does so. To assist her it is usual to hang or drape a stack of towels on a simple bar supported at the feed end of the ironing machine, but towels so draped must hang evenly on both sides or they fall off. Also their feed ends are concealed and difficult to find and feed.

According to my invention, the supporting device on which the articles are laid holds them with their feed ends clearly in view and close to the feeding apron, without chance of their falling away.

The supporting device shown includes two like

2

arms 12, made of metal straps and provided with slots 13 through which securing screws 13a may be threaded into the folding machine frame for attaching the support to the machine in the most convenient position. To the outer ends of these arms, which are turned up, I secure two end plates 14 lying in parallel planes and cross-connected by two rods 15 and a sheet metal housing 16, the latter having two holes or slots 17

10 in the convex smooth surface which it presents upwardly and toward the folding machine.

In the end plates 14 and arms 12 are journalled two eccentric trunnions 18, indicated by the dotted lines in Figs. 4 and 5, on the ends of a shaft 19 provided at one end with an operating handle 20 by means of which it may be rotated. Shaft 19 is of larger diameter than its end trunnions 18, and it turns within round openings in two blocks or plates 21, each having two holes 22 through which extend the frame rods 15. On the blocks 21 are secured card cloth members 23, two on each block, the wires 24 on such members having their bent ends extending upwardly or toward the operator. Collars 25 attached to shaft 19 prevent movement of the blocks endwise upon the shaft, while rods 15 compel the blocks, when they are adjusted, to always maintain parallel relation with the exposed face of the housing.

30 Along one edge of the housing I secure one edge of a flexible apron 26 by a fastening strip 26a. The other edge of the apron is wound upon a bar 27 the ends of which are mounted in brackets 28 fastened to the folding machine frame. This apron is extra long, providing excess material which hangs down and forms a bag to support the towels, as shown in Fig. 1. The depth of the bag may be varied, for towels of different length by winding the free end excess upon bar 27. Unwinding is prevented by making the bar square and correspondingly shaping the brackets 28. A pin 29 at each end of the bar prevents its endwise escape.

By grasping the knobbed handle 20 and turning it to its down position, shown in Fig. 5, the card cloth elements are withdrawn from the slots 17 through which they normally project and thus offer no resistance to adjustment of a stack of towels over the smooth face of the housing to 50 their correct feeding position, shown in dotted lines, Fig. 1. Then the handle is turned up to its normal position, Fig. 4. By reason of the eccentricity in shaft 19, this operation advances the card cloth elements to a position where they extend through slots 17 and engage the lowermost

towel in the stack, thus preventing the stack from sliding off. The advance end edges of the towels are not only exposed to view and easy to grasp, but they also are very close to the feed apron of the folding machine, requiring but very little movement by the operator to start them through that machine.

The apron or bag 26, of course, supports the lower portions of the towels, and naturally is adjusted according to their length.

It should also be noted that the card cloth elements are so arranged that as they rise they present their bent back faces into contact with the bottom article of the stack, thus avoiding catching or tearing the material while the blocks are advanced to operating position.

What I claim is:

1. A work support for holding articles to be fed to an operating machine, comprising a frame adapted for mounting at the feed end of the machine, a housing presenting a smooth convex surface sloping downwardly toward the machine and provided with an opening, and a friction device mounted in the housing and projecting through said opening.

2. A work support for holding articles to be fed to an operating machine, comprising a frame adapted for mounting at the feed end of the machine, a housing presenting a smooth convex surface sloping downwardly toward the machine and provided with an opening, and a friction device mounted in the housing and movable through said opening to either present it to articles to be fed or to withdraw it to a retracted position within the housing.

3. A work support for holding articles to be fed to an operating machine, comprising a frame adapted for mounting at the feed end of the machine, a housing presenting a smooth convex surface sloping downwardly toward the machine and provided with an opening, a friction device mounted in the housing and movable through said opening to either present it to articles to be fed or to withdraw it to a retracted position within the housing, and a manually operatable handle for said device.

4. A work support for holding articles to be fed to an operating machine, comprising a frame adapted for mounting at the feed end of the machine, a housing presenting a smooth convex surface sloping downwardly toward the machine and provided with an opening, and a card cloth retainer movable through said opening.

5. A work support for holding articles to be fed to an operating machine, comprising a frame adapted for mounting at the free end of the machine, a housing presenting a smooth convex surface sloping downwardly toward the machine and provided with an opening, a friction device

mounted in the housing and projecting through said opening, and a flexible apron depending from said housing and adapted for supporting the lower ends of articles lying upon the housing.

6. A work support for holding articles to be fed to an operating machine, comprising a frame adapted for mounting at the free end of the machine, a housing presenting a smooth convex surface sloping downwardly toward the machine and provided with an opening, a card cloth retainer movable through said opening, and a flexible apron depending from said housing and adapted for supporting the lower ends of articles lying upon the housing.

7. A work support for holding articles to be fed to an operating machine, comprising a frame adapted for mounting at the free end of the machine, a housing presenting a smooth convex surface sloping downwardly toward the machine and provided with an opening, a friction device mounted in the housing and projecting through said opening, and a flexible apron depending from said housing and adapted for supporting the lower ends of articles lying upon the housing, said apron being provided with means for adjusting its effective length.

8. A work support for holding articles to be fed to an operating machine, comprising a frame adapted for mounting at the free end of the machine, a housing presenting a smooth convex surface sloping downwardly toward the machine and provided with an opening, a card cloth retainer movable through said opening, and a flexible apron depending from said housing and adapted for supporting the lower ends of articles lying upon the housing, said apron being provided with means for adjusting its effective length.

9. A work support for holding articles to be fed to an operating machine, comprising a frame adapted for mounting at the feed end of the machine, a housing presenting a smooth convex surface sloping downwardly toward the machine and provided with an opening, a card cloth retainer movable through said opening, and an operating shaft mounted in the housing for adjusting said retainer.

10. A work support for holding articles to be fed to an operating machine, comprising a frame adapted for mounting at the feed end of the machine, a housing presenting a smooth convex surface sloping downwardly toward the machine and provided with an opening, a card cloth retainer movable through said opening, and an operating shaft mounted in the housing for adjusting said retainer, said shaft being rotatable and eccentrically mounted in the housing.

Certificate of Correction

Patent No. 2,476,094

July 12, 1949

ALBERT N. HOFFMANN

It is hereby certified that errors appear in the printed specification of the above numbered patent requiring correction as follows:

Column 3, line 56, and column 4, lines 7, 17, and 29, for the word "free" read *feed*;

and that the said Letters Patent should be read with these corrections therein that the same may conform to the record of the case in the Patent Office.

Signed and sealed this 31st day of January, A. D. 1950.

[SEAL]

THOMAS F. MURPHY,
Assistant Commissioner of Patents.
